JACK

Wilbur Jackson, Chatsworth, Ga.

Application December 22, 1945, Serial No. 636,778

2 Claims. (Cl. 254—126)

1

My invention relates to lifting jacks.

An important object of the invention is to provide a lifting jack which is well adapted for use with automobiles or other motor vehicles.

A further object of the invention is to provide a jack which is low when collapsed and may be conveniently inserted beneath the automobile to raise the same.

A further object of the invention is to provide a jack having opposed toggles which are operated by a rod having a single continuous thread, in combination with a ball-bearing to take the end thrust.

A further object of the invention is to provide a handle having a transverse pivot element, to be removably inserted within a transverse opening formed in a coupling, which is pivoted to the screw threaded rod at a right angle to the pivot element, thereby affording a universal joint, and a detachable connection between the handle and coupling which will not readily separate in use.

A further object of the invention is to provide means whereby the strain or torque of the handle sections is transmitted directly to the coupling-sleeve, thus removing the same from the pins which connect the handle sections with the coupling-sleeve.

A further object of the invention is to provide means for retaining the upper links of one toggle parallel with the lower links of the other toggle, while the toggles are opened and closed.

A further object of the invention is to secure the collar which is arranged behind the end-thrust bearing to the screw threaded rod by means of two rivets or pins, arranged at substantially a right angle to each other, affording a stronger construction than can be obtained by using a larger single rivet or pin.

Other objects and advantages of the invention will be apparent during the course of the following description.

In the accompanying drawings, forming a part of this application, and which like numerals are employed to designate like parts throughout the same,

Figure 1 is a side elevation of a jack embodying my invention.

Figure 2 is a plan view of the same.

Figure 3 is a central vertical longitudinal section through the jack, and,

Figure 4 is a side elevation of the handle removed, parts in section,

Figure 5 is an enlarged transverse section on line 5—5 of Figure 3,

2

Figure 6 is a similar view on line 6—6 of Figure 4.

In the drawings, wherein for the purpose of illustration, is shown a preferred embodiment of my invention, the numeral 5 designates a base, carrying vertical sides or flanges 6, spaced as shown. Arranged above the base 5 is a head or rest 7, including spaced vertical sides 8.

Disposed in opposed relation are toggles 9. One toggle 9 includes a pair of upper links 10 and a pair of lower links 11. These links 10 and 11 are provided at their inner ends with gear teeth 12. The links 10 and 11 are duplicates and interchangeable. The other toggle 9 comprises upper and lower pairs of links, 13 and 14, having gear teeth 15.

The links 13 and 14 are duplicates and interchangeable, but the links of one toggle are not duplicate and are not interchangeable with the links of the other toggle, since the gear teeth arrangement is different.

At their inner ends, the pairs of links 11 and 14 are pivotally mounted upon horizontal transverse pins 16, secured to the sides 6, and these pins 16 carry spacers 17. At their inner ends, the pairs of links 10 and 13 are pivotally mounted upon horizontal transverse pins 18, secured to the sides 8, and these pins carry spacers 19. The gear teeth 12 of the links 10 mesh with the gear teeth 15 of the links 13 and the gear teeth 12 of the links 11 mesh with the gear teeth 15 of the links 14.

The toggles 9 are operated by a horizontal rod 20, having a single screw thread 21. The screw threaded portion 21 of the rod operates within a screw threaded opening 22 formed in a head or block 23, provided at its opposite ends with pivot elements or trunnions 24, pivotally connected with the outer ends of the pairs of links 10 and 11. These trunnions carry washers 25 and the ends of the trunnions are swaged or spread. The numeral 26 designates a block or head provided with a smooth opening 27, for rotatably receiving a smooth reduced portion 28 of the rod 20. The block or head 26 is provided at its opposite ends with pivots or trunnions 29, pivotally connected with the outer ends of the pairs of links 13 and 14, and carrying washers 30. The pivots or trunnions have their outer ends spread or swaged. The block or head 26 is provided with an outer flat 32. A collar 33 is formed integral with the rod 20, affording a shoulder, and is arranged between the screw thread 21 and the block or head 26. The reduced smooth portion 28 also carries a collar 34, secured thereto by two pins

35, arranged at a right angle to each other. By employing these two pins a stronger connection is afforded than could be effected by the use of a single pin of larger size. Arranged inwardly of and next to the collar 34 is an end thrust ball bearing 36, carried by the smooth reduced portion 28 of the rod. Washers 37 are arranged between the end thrust ball bearing and the flat 32.

The smooth reduced portion 28 of the rod 20 is provided adjacent to the collar 34 with an extension 38, having opposite flat faces, and this extension projects into a recess 39 of a coupling 40, and is pivotally connected with the coupling by a pin 41, the ends of which are spread or swaged. The coupling 40 is provided near its outer end with a transverse cylindrical opening 42, arranged at a right angle to the pin 41.

The numeral 43 designates a handle, formed in sections 44 and 45. The section 45 has a hard crank 46. The section 44, at its free end, is bent to provide a diagonal portion 47 and a transverse portion 48, disposed at a right angle to the section 44. The transverse portion 48 has a transverse opening 49, receiving a spring pressed ball 50, to project a short distance beyond the periphery of the transverse portion 48, to enter an annular recess 51, formed in the coupling 40 and this recess 51 leads into the opening 42. The transverse portion 48 is cylindrical and when inserted within the cylindrical opening 42, it is pivotally mounted therein, the ball 50 traveling in the annular groove or depression 51. The transverse portion 48 is therefore detachably held within the opening 42. Since the transverse portion 48 and pivot element or pin 41 are at a right angle to each other, the handle 43 has a universal connection with the rod 20.

At its inner end, the handle section 44 is bent to provide a lateral extension 52 and the handle section 45 is bent to provide an inner lateral extension 53. These lateral extensions 52 and 53 are arranged within a coupling-sleeve 54, having spaced parallel sides 55, open at their bottoms. The lateral extension 52 is secured to the sides 55 by a pin or rivet 54, and a pin or rivet 55 connects the sides 55 and is arranged upon that side of the handle section 44, remote from the closed side of the coupling-sleeve 54. The lateral extension 53 is pivotally connected with the sides 55 by means of a pin or rivet 56. The handle section 45 carries a lock-ring 57, slidable thereon, and having its outward movement limited by stop plugs 58. This lock-ring is shiftable over stops 59, carried by the sides 55. When the lock-ring 57 engages over the stops 59, the handle section 45 cannot be folded or broken upon its pivot 56, and hence may be conveniently employed to turn the rod 20. The strain or torque from the shaft sections 44 and 45 is transmitted directly by the lateral extensions 52 and 53 to the sides 55 of the sleeve-coupling, and is taken off of the pins or rivets 54 and 56. When the handle is not in use, it is collapsed by moving the lock-ring 57 out of engagement with the stops 59 and then swinging the handle section 45 upon its pivot 56 over the handle section 44.

The operation of the jack is as follows:

The transverse portion 48 is inserted within the opening 42, and the handle 43 is employed to

rotate the rod 20. The rod having screw threaded engagement with the block or head 23 feeds longitudinally to the left, Figure 3, with respect to this block. The thrust from the block 26 is transmitted to the collar 34 through the end thrust bearing 36. This end thrust bearing provides a jack which is very free and easy to operate.

Since the links of one toggle joint are geared to the corresponding links of the other toggle, the upper links of one toggle remain parallel with the lower links of the other toggle, and the head or rest 8 remains horizontal, as the toggles are spread, and collapsed.

It is to be understood that the form of my invention herewith shown and described is to be taken as a preferred example of the same and that various changes in the shape, size, and arrangement of parts may be resorted to without departing from the spirit of my invention or the scope of the subjoined claims.

Having thus described my invention, what I claim is:

1. A jack, comprising opposed toggles, a base pivotally supporting the lower ends of the toggles, a head pivotally mounted upon the upper ends of the toggles, means to move the toggles including a rotatable rod, a coupling, a pin pivotally connecting the coupling with the rod, said coupling being provided with a transverse opening having its longitudinal axis arranged at substantially a right angle to the longitudinal axis of the pin and a handle having a transverse portion adapted to be inserted within the opening, and pivotally mounted therein, the arrangement being such that the handle has a detachable universal connection with the rod.

2. A jack, comprising opposed toggles, a base pivotally supporting the lower ends of the toggles, a head pivotally mounted upon the upper ends of the toggles, means to move the toggles including a rotatable rod, a coupling having a transverse opening, a pin pivotally connecting the coupling with the rod and having its longitudinal axis arranged at substantially a right angle to the longitudinal axis of the opening, said coupling having an annular groove leading into the opening, a handle having a transverse portion to be pivotally mounted within the opening, a spring pressed ball carried by the transverse portion to enter the annular groove, the arrangement being such that the handle has a detachable universal connection with the rod.

WILBUR JACKSON.
